ATTORNEY

UNITED STATES PATENT OFFICE.

DAVID L. RANLETT, OF NEW YORK, N. Y., ASSIGNOR TO AMERICAN BALSA COMPANY, INC., A CORPORATION OF NEW YORK.

AQUA-PLANE.

1,356,013.

Specification of Letters Patent. Patented Oct. 19, 1920.

Application filed February 7, 1920. Serial No. 356,842.

To all whom it may concern:

Be it known that I, DAVID L. RANLETT, a citizen of the United States, and a resident of the borough of Manhattan, city, county, 5 and State of New York, have invented certain new and useful Improvements in Aqua-Planes, of which the following is a specification.

This invention relates to improvements in 10 aqua-planes.

One of the objects of my invention is to produce an aqua-plane which is built up or provided with walls about the bow so as to deflect spray or water during its progress 15 on the water; to prevent the turning down or burying of the bow of the said aqua-plane and to make it easier for the plane to rise from the surface of the water.

Another object of my invention is to produce 20 an aqua-plane which, while embodying the required strength, rigidity and power of resistance to strains and shocks encountered in use, will also possess greater lightness in weight and greater buoyancy than 25 aqua-planes of similar proportions heretofore used. This aqua-plane will, therefore, support on the water a relatively heavier load than such aqua-planes; will rise from the water with a given load at less speed or 30 conversely will so rise at a given speed with a greater load, and will at a given speed with a given load remain longer in the air or take greater flights, thus greatly adding to the degree and possibilities of sport which 35 may be obtained by the use of an aqua-plane.

With these and other objects in view, the invention comprises the combination of 40 members and arrangement of parts so combined as to co-act and coöperate with each other in the performance of the functions and the accomplishment of the results herein contemplated, and comprises in one of its adaptations the species or preferred form 45 illustrated in the accompanying drawings, in which:

Figure 1 is a plan view of an aqua-plane embodying my invention;

Fig. 2 is a side elevation of the plane 50 shown in Fig. 1;

Fig. 3 is a longitudinal section on the line 3—3 of Fig. 1; and

Fig. 4 is an enlarged section on the line 4—4 looking forwardly.

Referring now to these drawings, which 55 illustrate a preferred embodiment of my invention, 1 indicates an aqua-plane which comprises a centrally disposed panel 2 preferably of a configuration similar to that of the completed aqua-plane. This panel is 60 composed of balsa wood or similar light wood which has been treated to preserve it and make the same waterproof. This wood readily absorbs water and therefore preferably is treated with paraffin material to 65 preserve and make it waterproof. This is preferably accomplished in accordance with the process described in Reissue Letters Patent No. 13,952 of Robert A. Marr. This panel is also preferably covered with a cov- 70 ering 2^a of canvas or similar tough covering material.

Said balsa wood panel, while possessing 75 desirable characteristics of lightness in weight and great structural strength relatively to its weight, is relatively soft and pithy in structure and offers but little resistance to fracture or depression. I therefore surround the edges of the panel 2 of balsa wood with a marginal frame 3 preferably composed of oak or other tough 80 wood. In securing the frame to the balsa wood panel I preferably place the canvas cover 2^a over the upper surface and edges of the balsa wood panel and force the oak 85 frame, which closely fits said panel, downwardly over the said balsa wood panel so as to secure the canvas covering initially in place. Said panel and marginal frame are fastened together and the balsa panel is reinforced by a series of suitably-spaced dowels or rails 4 composed of a suitable tough 90 wood and extending transversely from one side of the frame to the other through the intermediate panel, the ends of said dowels 95 being seated in bores in the frame. The canvas and frame are further fastened to the panel by a series of short dowels 5 which are driven through bores 5^a in the frame, through the edge of the canvas and 100 into the balsa wood panel. The frame 3 is thus securely fastened to the balsa wood panel 2 without the use of nails or other metallic fastening devices which would, in use, rust and become ineffective. The rear 105 corners of the frame are preferably held together by stove bolts 6, the body and heads of which are inclosed in a suitable bore, the

ends of which are closed at opposite ends by oak plugs 7 to prevent access of water to the bolts.

In the preferred embodiment of my invention shown, the aqua-plane is substantially flat and in configuration has its rear and amidship section substantially rectangular and a bow curving inwardly from the forward end of the amidship section to a point. In use, the conventional aqua-plane, under certain conditions, buries its nose and causes difficulty in manipulation and also spray is often dashed with great force into the face of the user. To obviate this nose-burying, to deflect spray and also to assist or make it easier to rise from the water, I provide at the bow shallow walls 8-8^a which, as illustrated, extend forwardly from a point at which the towing line is attached, incline upwardly and outwardly somewhat from the bottom thereof and gradually increase in height from said towing point to the prow of the aqua-plane. These walls are preferably formed of oak or other suitable tough material and are preferably set into a seat provided therefor in the frame at the said bow portion. As shown, the walls are reinforced at the prow by a triangular-shaped block 9 of oak or like material resting on the frame and suitably secured to the walls at the point where such opposite walls meet.

Suitable hardware for fastening, towing and manipulating ropes is provided and as illustrated double-eye plates 10 are fastened to the oak frame at opposite sides thereof. To one pair of eyes 10^a of said plates, a towing rope 11 is suitably fastened and to the other pair of eyes 10^b a manipulating rope 12 is likewise suitably fastened.

It will be seen that I have provided an aqua-plane which, while embodying the required strength and rigidity and power of resistance to the unusual strains and shocks encountered in the use of such a device, will also possess greater lightness in weight and greater buoyancy than aqua-planes of similar proportions heretofore used. Furthermore, my improved aqua-plane will support on the water a relatively heavier load than such other aqua-planes; will rise from the water with a given load at less speed, or conversely will so rise at a given speed with a greater load and will at a given speed with a given load remain longer in the air or take greater flights than has heretofore been possible with aqua-planes of similar proportions; and it will be obvious that I have thus greatly added to the degree and possibilities of the sport of aqua-planing.

It will also be seen that by the use of the walls 8-8^a along the bow, I have provided means which will prevent the burying of the nose of the aqua-plane; will deflect spray

and will, because of the additional resistance offered to the water, make it easier for the aqua-plane to rise from the water.

Having described my invention, I claim:

1. An aqua-plane or like device comprising a centrally-disposed panel composed of an extremely light, soft, readily fracturable and porous wood which has been treated to preserve and make it waterproof and a marginal frame of a relatively tough and tenacious wood fastened at the edges of said panel.

2. An aqua-plane or like device comprising a centrally-disposed panel composed of an extremely light, soft, readily fracturable and porous wood which has been treated to preserve and make it waterproof, a marginal frame of a relatively tough and tenacious wood fastened at the edges of said panel and means connected to said frame for manipulating said aqua-plane.

3. An aqua-plane comprising a panel composed of balsa wood which has been treated to preserve and make it waterproof, and a marginal frame of a relatively tough and tenacious wood securely fastened around the edges of said panel.

4. An aqua-plane comprising a panel composed of balsa wood which has been treated to preserve and make it waterproof, a covering of tough material for the upper surface of said balsa wood panel, and a marginal frame of a relatively tough and tenacious wood securely fastened around the edges of said panel.

5. An aqua-plane comprising a panel composed of balsa wood which has been treated to preserve and make it waterproof, a marginal frame of a relatively tough and tenacious wood securely fastened around the edges of said panel by means of a series of wooden dowels extending transversely through said frame into said panel.

6. An aqua-plane or like device comprising a panel composed of balsa wood which has been treated to preserve and make it waterproof, a marginal frame of a relatively tough and tenacious wood securely fastened around the edges of said panel by means of a series of wooden dowels extending transversely from one side of the aqua-plane to the other through said panel and frame.

7. An aqua-plane or like device comprising a panel composed of balsa wood which has been treated to preserve and make it waterproof; a marginal frame of a relatively tough and tenacious wood securely fastened around the edges of said panel and means connected to said frame for manipulating said aqua-plane.

8. An aqua-plane or like device comprising a flat panel composed of balsa wood which has been treated to preserve and make it waterproof, and having a pointed prow

and a substantially rectangular rear portion; a marginal frame of similar configuration and composed of a relatively tough and tenacious wood securely fastened around the edges thereof and means connected to said frame for manipulating said aqua-plane.

9. An aqua-plane or like device comprising a panel composed of balsa wood which has been treated to preserve and make it waterproof and having a pointed prow and rectangular rear portion; a covering of tough material for the upper part of said balsa wood panel; a marginal frame of similar configuration and composed of a tough and tenacious wood adapted to fit over the edges of said panel; means for fastening said panel frame and covering together, and means connected to said frame for manipulating said aqua-plane.

10. An aqua-plane or like device comprising a panel composed of balsa wood which has been treated to preserve and make it waterproof, and having a pointed prow and rectangular rear portion, a covering of tough material for the upper part of said balsa wood panel, a marginal frame of similar configuration and composed of a tough and tenacious wood securely fastened around the edges thereof, fastening means for connecting said marginal frame, covering and panel together including a series of wooden dowels extending transversely from one side of the aqua-plane to the other through said panel and frame; and means connected to said frame for manipulating said aqua-plane.

11. An aqua-plane having a body portion of suitable configuration and side walls rising from the body portion at the prow.

12. An aqua-plane having a pointed bow

and provided with shallow side walls built up along said pointed bow.

13. An aqua-plane having a pointed bow with walls built up along said pointed bow inclining outwardly and gradually rising 45 from the points of attachment of the towing rope to the prow.

14. An aqua-plane having a substantially flat and rectangular body portion and a bow curved inwardly from said body portion 50 and provided with shallow walls built up along said pointed bow.

15. An aqua-plane having a substantially flat and rectangular rear and amidship sections and a bow curved inwardly from said 55 amidship sections and walls inclining outwardly and upwardly built up along said bow and gradually diminishing in height from the prow to the rear end thereof.

16. An aqua-plane or like device comprising a buoyant panel composed of an extremely light, soft, readily fracturable and porous wood and a reinforcing portion of relatively tough and tenacious material secured to said buoyant panel. 60

17. An aqua-plane or like device comprising a buoyant panel composed of an extremely light, soft, readily fracturable and porous wood and a reinforcing portion of relatively tough and tenacious material secured to said buoyant panel and manipulating means for said aqua-plane connected to said reinforcing portion. 65

In witness whereof, I have signed my name to the foregoing specification in the 70 presence of two subscribing witnesses.
